HOLDER FOR A DISPOSABLE DRINKING CUP

Rodney E. Ludder, Glen Head, N.Y., assignor to Owens-Illinois, Inc., Toledo, Ohio

Filed Apr. 16, 1970, Ser. No. 22,469

Term of patent 14 years

Int. Cl. D7—01

U.S. Cl. D44—10

FIG. 1

FIG. 2

FIG. 1 is a perspective view of a holder for a disposable drinking cup showing my new design;

FIG. 2 is a front elevational view; and

FIG. 3 is a top plan view.

I claim:

The ornamental design for a holder for a disposable drinking cup, substantially as shown.
